UNITED STATES PATENT OFFICE.

JOHN W. KERR, OF ORLANDO, FLORIDA.

QUICKLY-ADJUSTABLE STIRRUP-LEATHER.

1,072,958.

Specification of Letters Patent.

Patented Sept. 9, 1913.

Application filed August 6, 1913. Serial No. 783,365. **REISSUED**

To all whom it may concern:

Be it known that I, JOHN W. KERR, citizen of the United States, residing at Orlando, in the county of Orange and State 5 of Florida, have invented certain new and useful Improvements in Quickly-Adjustable Stirrup-Leathers, of which the following is a specification.

The present invention relates in general 10 to harness, and more particularly to a quickly adjustable buckleless leather or strap connection for stirrups and the like, the object of the invention being to provide a strap connection of this character which 15 embodies novel features of construction whereby the necessity of using a buckle and weakening the strap by a number of openings therein is entirely eliminated and friction is utilized to lock the strap in an 20 adjusted position, the strap connection being susceptible of being instantly lengthened or shortened as required.

A further object of the invention is to 25 provide a strap connection of this character which is simple and inexpensive in its construction, which will positively hold an adjustment under the most trying conditions of use, and which will withstand hard usage without danger of breaking or becoming 30 unduly worn.

With these and other objects in view, the 35 invention consists in certain novel combinations and arrangements of the parts as will more fully appear as the description proceeds, the novel features thereof being pointed out in the appended claims.

For a full understanding of the invention, reference is to be had to the following 40 description and accompanying drawing, in

Fig. 1 is a perspective view of a stirrup leather constructed in accordance with the invention, showing the manner of grasping the same to lengthen or shorten the leather. 45 Fig. 2 is a front elevation of the stirrup leather. Fig. 3 is a side elevation of the stirrup leather. Fig. 4 is a side elevation of a stirrup leather showing a slight modification, portions being broken away, and 50 Fig. 5 is a detail view of the friction member employed in the modification.

Corresponding and like parts are referred in the following description and indicated in all the views of the drawing by the same reference characters.

55

For convenience in illustrating the invention it has been shown as embodied in a stirrup leather, although it will be understood that the invention is not restricted to stirrup leathers, but may be utilized in connection with check reins, traces, backbands, girths, or wherever a quickly adjustable strap connection of this character would be desirable.

Referring to the drawing, the numeral 1 65 designates the supporting ring or eye at the upper end of the stirrup leather, 2 the stirrup proper which is of the conventional construction and is formed with the stirrup eye 3, and 4 the friction ring. The strap 5 70 is threaded through the supporting ring or eye 1, the stirrup eye 3, and the friction ring 4 so as to produce a number of friction points, one end of the strap being secured to one of the end eyes, while the other end 75 of the strap is secured to the friction ring 4. In the present instance, the upper end of the strap 5 is secured at 6 to the friction ring 4. From this point the strap is extended upwardly at 5^a, threaded through the supporting ring or eye 1 and carried downwardly at 5^b, threaded through the stirrup eye 3, and carried upwardly at 5^c, threaded 80 through the friction ring 4 and carried downwardly at 5^d, the opposite end of the 85 strap being secured at 7 to the stirrup eye 3.

With the foregoing construction it will be seen that there are three thicknesses of leather between the friction ring 4 and the stirrup eye 3, and two thicknesses of leather 90 between the friction ring 4 and the supporting ring 1. A suitable retaining band or keeper 8 of leather or other suitable material surrounds the three thicknesses of leather between the friction ring 4 and the 95 stirrup 2 so as to hold the same together. With this manner of looping the strap, a friction point is produced at A where the strap passes through the supporting eye 1, a second friction point at B where the strap 100 passes through the stirrup eye 3, and a third friction point at C where the strap passes

through the friction ring 4. At the friction point B, it will be observed that the looped portion of the strap which is threaded through the stirrup eye 3 bears against and frictionally engages the end 7 of the strap which is permanently connected to the stirrup eye, thereby producing a very effective friction lock at this point. These three frictions produce a positive lock which causes the strap to hold an adjustment, regardless of the amount of pressure which is applied to the stirrup or the tension to which the strap is subjected. However, by grasping the portion 5^b of the strap, as indicated by dotted lines upon Fig. 1, the length of the stirrup leather may be instantly increased or decreased as found desirable. By pulling downwardly upon the portion 5^b of the strap and moving the friction ring 4 toward the supporting ring 1 so as to increase the portion of the strap connection having three thicknesses, the length of the strap is shortened, while by pulling upwardly upon the portion 5^b of the strap and moving the friction ring 4 toward the stirrup so as to decrease the portion of the stirrup leather having three thicknesses, the length of the stirrup leather is increased. This adjustment can be made instantly and the adjustment will be positively retained by the stirrup leather regardless of the tension under which the same may be placed. There is no necessity for providing a buckle and weakening the strap by a series of openings therein, and neither are there any free strap ends to project outwardly and cause annoyance.

A slight modification is shown by Figs. 4 and 5, in which 1^a designates the supporting ring, 2^a the stirrup, and 3^a the stirrup eye. The friction ring 4^a is shown as embodying a number of cross bars through which the strap may be threaded. The strap 9 has one end thereof secured at 10 to the friction ring 4^a, is carried upwardly at 9^a, threaded through the supporting ring 1^a and carried downwardly at 9^b, threaded through the stirrup eye 3^a and carried upwardly at 9^c, the end thereof being secured at 11 to the supporting eye 1^a, while an intermediate part of the portion 9^c is threaded through the cross bars of the friction ring 4^a. By releasing the tension in the strap so as to loosen the friction grip of the strap upon the ring 4^a, the said ring 4^a can be raised and lowered upon the portion 9^c of the strap so as to increase or decrease the length of the stirrup leather.

While I have illustrated and described two forms or embodiments of the invention, it will be understood that there are numerous other possible manners of constructing the looped strap connection and that many minor changes can be made in the construction thereof without departing in any manner from the spirit of the invention.

Having thus described the invention, what I claim as new and desire to secure by Letters Patent, is:

1. A quickly adjustable buckleless leather for stirrups and the like, including end members, an intermediate friction member, a looped strap threaded through the end members and the friction member so as to frictionally engage the same, one end of the strap being connected to one of the end members while the opposite end thereof is connected to the friction member, and a keeper applied to the looped strap to hold the various thicknesses thereof together. 70

2. A quickly adjustable buckleless leather for stirrups and the like, including end members, a friction ring, a looped strap threaded through the end members and friction ring so as to frictionally engage the same, one end of the strap being connected to one of the end members while the opposite end thereof is connected to the friction ring, and a keeper applied to the looped strap to hold the various thicknesses thereof together. 85

3. A quickly adjustable buckleless leather for stirrups and the like, including end attaching eyes, an intermediate friction ring, and a flat strap threaded through the end attaching eyes and the friction ring so as to frictionally engage the same, one end of the strap being connected to one of the end attaching eyes while the opposite end of the strap is attached to the friction ring, the end of the strap which is attached to the end attaching eye fitting under and frictionally engaging the looped portion of the strap which is threaded through the said end attaching eye. 95

4. A quickly adjustable buckleless leather for stirrups and the like including end attaching eyes, a friction ring, a looped strap having one end thereof secured to the friction ring, the said strap being then carried to one of the end attaching eyes, threaded through the same and carried to the opposite end attaching eye, threaded through the second end attaching eye and carried to the friction ring, threaded through the friction ring and carried to the second end attaching eye to which it is secured, whereby two thicknesses of strap are provided between the friction ring and the first end attaching eye, and three thicknesses of strap between the friction ring and second end attaching eye, and a keeper surrounding the looped strap to hold the different thicknesses thereof together. 105 110 115

5. A quickly adjustable buckleless leather for stirrups and the like, including end attaching members, an intermediate friction ring, and a flat strap, one end of the strap being secured to the friction ring and the strap being then carried toward one of the end attaching members and threaded through the same, carried to the opposite 120 125 130

end attaching member and threaded through the same, carried to the friction ring and threaded through the same, and then carried to the second mentioned end attaching member and secured thereto, the looped portion of the strap which is threaded through the said second mentioned end attaching member being arranged to produce sufficient fric-

tion by contact with the attaching member to prevent slipping. 10

In testimony whereof I affix my signature in presence of two witnesses.

JOHN W. KERR.
